GAS COCK

Ervin H. Mueller, Grosse Pointe Park, Mich.

Application September 9, 1938, Serial No. 229,073

4 Claims. (Cl. 251—109)

This invention relates to a valve and particularly to a valve of the type useful as a gas cock for controlling the supply of gas to a gas burner.

The invention is directed especially to the provision of a valve for controlling a supply of gas to a double burner wherein a small supply of gas is furnished to what may be termed a simmering burner and a larger supply of gas is furnished to a burner for a larger flame. The valve comprises a valve body with a valve plug rotatable between extreme positions, one of which is "off" and one of which is "on." As the rotatable valve member is moved from "off" position, ports or passageways are aligned, first for supplying a small supply of gas to a simmering burner. As the rotatable valve member is further operated, it eventually reaches the full "on" position, at which point ports or passageways are aligned for the supply of gas to the main or large burner. The small supply of gas for the simmering burner, however, is not cut off once it is opened, with the result that gas is supplied to the simmering burner at the time gas is also supplied to the main burner, and is supplied to the simmering burner during the operation of the valve from the position where the ports or passageways for the simmering burner are first opened to the full "on" position. To this end, what may be termed a hold-over port or passageway, is provided for the supply of gas to the simmering burner during this operation of the valve member.

In the accompanying drawing:

Fig. 1 is a cross sectional view taken through a valve member constructed in accordance with the invention illustrating the valve body, the rotatable valve member and some of the passageways.

Fig. 2 is a view taken substantially on line 2—2 of Fig. 1 with the cap removed to show underlying parts.

Fig. 3 is a cross sectional view illustrating some of the control mechanism.

Fig. 4 is an enlarged cross sectional view taken substantially on line 4—4 of Fig. 1 illustrating the parts in "off" position.

Fig. 5 is a view similar to Fig. 4 illustrating the parts in a position with the valve partially open for supplying gas to the simmering burner.

Fig. 6 is a cross sectional view similar to Fig. 5 showing the valve in a position through which it moves from the positions shown in Figs. 5 and 7.

Fig. 7 is a cross sectional view similar to Figs. 4 and 6, inclusive, showing the valve in full "on" position.

The gas cock has a body 1 provided with a tapered bore 2 for the reception of a tapered plug valve member 3. The valve member has an extension 4 which may be screw threaded for attachment to a gas supply line. The body also has a projection on one side as illustrated at 5, which is of angular formation as shown in Fig. 1, and this projection has a passageway 6 and an intersecting passageway 7. The passageways 6 and 7 may be drilled in the body through the end of the projection 5, and the end is closed by a plug 8. The passageway 6 leads into the valve chamber and the passageway 7 leads into the valve chamber near one end. An extension 9 has a passageway 10, which leads to a relatively large outlet jet structure generally illustrated at 11 of the usual construction. The body also has a projection which has a passageway 13. As illustrated, a tube 14 connects to the passageway 13 by means of a fitting 15, and on the end of the tube 20 is a relatively small gas jet structure generally illustrated at 16. Of course, whether or not the outlet jet 16 is attached directly to the projection 12 or is attached remotely through the means of a conduit or tube is a relative matter.

The rotatable valve member resides in the plug 3 which has a stem 20 having a D shape in cross section for the reception of a handle 21. This plug has a transverse passageway 22, and another passageway 23 connecting into passageway 22, 30 and a small passageway 24 which is countersunk or recessed in the outer face of the plug as at 25 forming an enlargement, the purpose of which will presently appear. There is no axial passageway through the plug, with the result that the small end of the valve chamber which connects into the passageway 7 is closed off by the plug from the remaining portion of the valve chamber.

The large jet 11 supplies a relatively large flow of gas to a main gas burner for frying or general cooking, while the small jet 16 supplies a small flow of gas to a secondary or smaller burner for simmering purposes. It is well known how these burners may be arranged on a gas stove, and therefore they are not shown. The valve is in "off" position as illustrated in Fig. 4, at which time the supply passageway 4 is closed by the plug. In the operation of the plug it is turned counterclockwise as Figs. 2 and 4 to 7 are viewed, 50 and when the valve reaches a position substantially as shown in Fig. 5 gas flows from the passageway 4 into the end of the passageway 22 through passageway 23 and passageway 13, and thence through the jet 16 to the simmering

burner. The main burner remains closed because the passageway 6 is closed. The valve may then be rotated further counterclockwise to its limit of rotation where it takes the position substantially as shown in Fig. 7. In this position gas flows in through the passageway 23 into passageway 22 and out through the passageway 13 to the simmering burner. Also, gas flows through passageways 6 and 7 to the small end of the valve 5 chamber, into passageway 10, and out through the passageway 11 to the main burner. Therefore, in this position both burners are turned on.

During the movement of the rotary valve member from the position of Fig. 5 to the position of Fig. 7, the supply of gas to the simmering burner is continued in an unbroken manner. The ports are arranged so that, before the passageway 23 moves out of registry with the passageway 13, the large portion 25 registers with passageway 13 so 10 that the gas flow into the passageway 13 is unbroken. Also, before the lower end of the passageway 22 (as Fig. 5 is viewed) moves out of registry with the passageway 4, passageway 23 moves into partial registry with the passageway 4, 15 thus continuing the flow of gas to the simmering burner. Upon continued movement, the upper end of the passageway 22 (as Figs. 5 and 6 are viewed) moves into partial registry with passageway 13 before the enlarged portion 25 moves out 20 of registry therewith to continue the flow of gas to the simmering burner, and when the passageway 22 approaches the position shown in Fig. 7 it registers with the passageway 6 and also registers with passageway 13. When the valve is 25 turned off the passageway 6 is first closed but the simmering burner is fed with gas successively through the passageway 22, enlargement 25 and passageway 23 until passageway 23 moves out of 30 registration with passageway 13.

In order to have the proper operation of a plug 35 valve of this kind which is spring pressed on to its seat, it is necessary that the surfaces of the plug and valve chamber be lubricated. Only a small passageway 24 is desired as a hold-over 40 port for the simmering burner, but this small passageway would be liable to plug up with grease if it opened directly at the periphery of the plug. The enlargement 25, however, is large enough to receive and retain some lubricant without blocking 45 the small passageway 24. Furthermore, the increased area provided by the enlargement 25 increases the feasibility of so positioning the ports that the passageway 13 remains connected to some one passageway in the plug from the time 50 the valve is initially turned on and through all of its "on" positions.

This valve, for the most approved operation, should be used with an arrangement for providing an intermediate stop in the simmering 55 position substantially as shown in Fig. 5. A cap 36 is secured to the valve body, through which the stem extends. Mounted on the D-shaped part of the stem for rotation therewith is a washer 31 which has a relatively long projection 32, and 60 an opposite shorter projection 33. A second washer 34 has two oppositely positioned projections in the form of cams 35 and 36, and this washer is keyed to the valve body by a projection 37. The washer 34 is axially shiftable but is held 65 against the washer 31 by a coil spring 38, which reacts against the valve body. A friction washer 70 is illustrated at 40 positioned between the cap and the washer 31. A sleeve 41 extends through the washer 34 and abuts against the washer 31 and is 75 acted upon by a coil spring 42. The spring reacts

against the sleeve and cap to urge the plug valve member against its seat.

The projections 35 preferably have slow lift cam faces on one side, as illustrated at 45, and quick lift cam faces on the opposite side as shown at 46. The valve body is cut away to provide a stop 48 and another stop 49.

In the "off" position the projection 32 strikes the stop 48. As the valve member is turned counter-clockwise the projections 32 and 33 strike the quick lift cam surfaces 46. This sets up a resistance and substantially stops the valve with the simmering burner on as shown in Fig. 5. By applying additional turning torque the projections ride over the quick lift cam surfaces and force 15 the washer 34 axially, compressing the spring 38. In the full "on" position, the projection 32 strikes the stop 49. The projection 33 is shorter than projection 32 and rides within the housing, and while it functions on the projection 35 it does 20 not function on the stops of the valve body. When the valve is turned off the projections ride easily over the slow lift cam faces 45 and 46. The valve can be nicely operated from "off" position to simmering position, with the projection 32 25 stopping the valve in one position and the quick lift cam surfaces stopping the valve in the other position. On the other hand, the valve may be operated from full "on" position to a simmering position with the projections stopping upon the 30 slow lift cam surfaces.

I claim:

1. A gas cock for controlling the flow of gas to a double gas burner comprising, a body having a valve chamber, an inlet passage leading to the chamber, a first outlet passage leading from the chamber, a second outlet passage leading from the chamber, a valve member rotatably disposed in the chamber and having a transverse passage extending therethrough, a second passage connecting into the transverse passage, said valve member being rotatable to, in one position, close the said inlet passage, in a second position to bring the transverse passage into registry with the inlet passage and the second passage in the 40 rotatable member into registry with the first outlet passage of the body, and in a third position to bring the second passage in the rotatable member into registry with the said inlet passage and the transverse passage into registry at opposite 45 ends with the first and second outlet passages of the valve body, and a small holdover port in the rotatable member connecting into the transverse passage and having an enlarged countersunk portion at the periphery of the rotatable member, 50 and arranged to register with the first outlet of the valve body in a position of the rotatable member intermediate the above mentioned second and third positions of the rotary valve members.

2. A gas cock for controlling the flow of gas to a double gas burner comprising, a body having a valve chamber, an inlet passage leading to the chamber, a first outlet passage leading from the chamber, a second outlet passage leading from the chamber, the inlet passage being disposed approximately at right angles to the outlet passages and the outlet passages being substantially diametrically opposite each other, a valve member rotatably disposed in the chamber and having a transverse passage extending therethrough, a second passage connecting into the transverse passage, said valve member being rotatable to, in one position, close the said inlet passage, in a second position to bring the trans- 75

verse passage into registry with the inlet passage and the second passage in the rotatable member into registry with the first outlet passage of the body, and in a third position to bring the second passage in the rotatable member into registry with the said inlet passage and the transverse passage into registry at opposite ends with the first and second outlet passages of the valve body, and a small hold-over port in the rotatable member connecting into the transverse passage and having an enlarged countersunk portion at the periphery of the rotatable member, and located circumferentially between one end of the transverse passage and the second passage in the rotatable member, and arranged to register with the first outlet of the valve body in a position of the rotatable member intermediate the above mentioned second and third positions of the rotary valve members.

20 3. A gas cock for controlling the flow of gas to a double gas burner comprising, a body having a valve chamber, an inlet passage leading to the chamber, a first outlet passage leading from the chamber, a second outlet passage leading from the chamber, a projection on one side in which the second outlet passage is located, a passage in the valve body axially disposed relative to the chamber, another passage in the said projection connecting the second outlet passage and the axially disposed passage, a valve member rotatably disposed in the chamber and having a transverse passage extending therethrough, a second passage connecting into the transverse passage, said valve member being rotatable to, 35 in one position, close the said inlet passage, in a second position to bring the transverse passage into registry with the inlet passage and the

second passage in the rotatable member into registry with the first outlet passage of the body, and in a third position to bring the second passage in the rotatable member into registry with the said inlet passage and the transverse passage into registry at opposite ends with the first and second outlet passages of the valve body, and a small hold-over port in the rotatable member connecting into the transverse passage and having an enlarged countersunk portion at the periphery of the rotatable member, and arranged to register with the first outlet of the valve body in a position of the rotatable member intermediate the above mentioned second and third positions of the rotary valve members. 15

4. A gas cock comprising a body having a valve chamber, an inlet passage leading to the chamber, outlet means leading from the chamber, a valve member in the chamber having passageways for the flow of gas therethrough from the inlet passage to the outlet means and including two ports angularly disposed relative to each other, said valve member being rotatable in the chamber whereby it may be positioned to close the inlet passage, to register one of the two ports with the inlet passage and to register the other of the two ports with the inlet passage for the control of the flow of gas to the outlet means, and auxiliary port means in the valve positioned between the said angularly disposed ports arranged to register with the inlet as the valve is moved from a position where one of the ports registers with the inlet passage to a position where the other port registers with the inlet passage for the continued flow of gas through the 30 gas cock at such time. 35
